Jacob Abbate, New York, N. Y.

Application July 29, 1938, Serial No. 78,943

Term of patent 3½ years

To all whom it may concern:

Be it known that I, Jacob Abbate, a citizen of the United States and a resident of the city of New York, in the county of New York and State of New York, whose post-office address is 1215 Fifth Ave., New York, city and State of New York, have invented a new, original, and ornamental Design for a Dress, of which the following is a specification, reference being had to the accompanying drawing, constituting a part thereof.

Fig. 1 is a front view of a dress showing my new design.

Fig. 2 is a rear view of the dress shown in Fig. 1.

The characteristic feature of my design resides in the specific woven embroidery on the waist and collar consisting of graduated horizontal stripes, the widest stripe being at the lowest end of the waist, as shown.

I claim:

The ornamental design for a dress, substantially as shown and described.

JACOB ABBATE.
